UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING ON SHOE-SOLES.

1,381,297.

Specification of Letters Patent. Patented June 14, 1921.

Application filed May 20, 1919. Serial No. 298,394.

To all whom it may concern:

Be it known that I, FREDERICK M. FURBER, a citizen of the United States, residing at Revere, in the county of Suffolk and State 5 of Massachusetts, have invented certain new and useful Improvements in Machines for Operating on Shoe-Soles; and I do hereby declare the following to be a full, clear, and exact description of the invention, such as 10 will enable others skilled in the art to which it appertains to make and use the same.

This invention relates to machines for operating on the marginal portions of shoe soles.

15 In the manufacture of shoes of the well known Goodyear or welted shoe type, in accordance with a process recently devised, the outsole is temporarily secured in position on the shoe bottom preparatory to stitching 20 the same to the welt by cementing the marginal portion of the outsole to the welt. In this process a coat of cement having been applied to the marginal portion of the outsole, or to the welt, or to both, the outsole 25 is placed on the shoe bottom and located in proper position relatively thereto, and the welt and the marginal portion of the outsole are then pressed firmly together to cause the same to adhere. The same procedure 30 may be followed in the manufacture of other types of shoes in cementing the marginal portion of an outsole to the sole portion of a shoe secured to and projecting beyond the body of the upper.

35 The primary object of the present invention is to produce a machine by which the operation of pressing together the marginal portion of an outsole and the welt or other sole portion of a shoe projecting beyond the 40 upper in cementing the same together may be performed in a rapid, efficient and reliable manner.

With the above object in view, an important feature of the present invention consists 45 in the provision of two sets of pressing devices for engaging and pressing together the marginal portion of an outsole and a sole portion of a shoe secured to and projecting beyond the upper arranged to act simultaneously and progressively on opposite sides of a shoe as the shoe is fed past said devices. With a machine embodying this

feature, the above operation may be performed upon both sides of a shoe at the same time with a resultant saving of considerable 55 labor and time of the operator.

The shoe may be fed past the pressing devices by the movement imparted thereto by the operator. Preferably, however, the shoe is fed automatically by the machine 60 so as to relieve the operator of unnecessary labor in subjecting the shoe to the operation of the machine. In the present machine the feeding mechanism is constructed and arranged to control at all times the feeding 65 movement of the shoe, thereby insuring a uniform movement of the shoe past the pressing devices. In the particular construction illustrated in the present application the pressing devices operate intermittently 70 to grip the marginal portion of the outsole and the projecting sole portion of the shoe between them, and the two sets of said devices are actuated alternately to feed the shoe. 75

Other features of the invention consist of certain novel and improved constructions, arrangements and combinations of parts hereinafter described and particularly pointed out in the claims the advantages of which 80 will be readily understood and appreciated by those skilled in the art.

The features of the invention will be clearly understood from the accompanying drawings illustrating a machine embodying 85 the invention in its preferred form and the following detailed description of the constructions therein shown.

In the drawings Figure 1 is a plan view partly in section of a machine embodying 90 the invention; Fig. 2 is a view in front elevation partly broken away and partly in section illustrating the rear portion of the machine; Fig. 3 is a view partly in side elevation and partly in section illustrating cer- 95 tain parts of the mechanism shown in Fig. 2; and Fig. 4 is a detail view in front elevation illustrating one set of pressing devices and certain associated parts.

In the construction illustrated in the 100 drawings each set of pressing devices comprises a support 2 shaped to enter the crease between the upper and the welt or other sole portion of a shoe secured to and pro-

jecting beyond the upper and a beater 4 arranged to engage the marginal portion of an outsole applied to the shoe bottom. To enable the supports to conform to the transverse curvature of the projecting sole portion of the shoe, each support 2 is secured to the upper end of a shaft 6 mounted to turn in a bearing 8 formed in an arm of a carrier 10. The supports are each yieldingly held normally in position with the work engaging surface thereof substantially parallel with the work engaging surface of the corresponding beater by means of a coiled spring 11 attached at one end to a collar 12 secured to the lower end of the shaft 6, and at its other end to a pin mounted in an arm 13 on the carrier 10. The beaters 4 are preferably made of yielding material such as rubber so that they will readily conform to the transverse curvature of the outsole.

Each beater 4 is rapidly reciprocated toward and from the corresponding support 2 during the operation of the machine and exerts intermittently a yielding pressure on the marginal portion of the outsole, thereby pressing the same firmly into contact with the projecting sole portion of the shoe. To enable the beaters 4 to yield when engaged with the marginal portion of the outsole each beater is secured in a slide 14 mounted to slide in guides in an oscillatory arm 15 and is acted upon by a coiled spring 16 surrounding a rod 18 to which the slide 14 is secured, the spring being interposed between the slide and the upper end of the guide-way therefor in the arm 15. The movement of the slide under the influence of the spring 16 is limited by the engagement of a nut 20 threaded on the upper end of the rod with the arm 15. Each of the arms 15 is pivoted on the corresponding carrier 10 and is rapidly oscillated during the operation of the machine to reciprocate the beaters.

At the beginning of the operation the two sets of pressing devices are located side by side, substantially in the relative positions shown in Fig. 1, and a shoe is presented thereto as indicated in dotted lines in this figure with the outsole and projecting sole portion of the shoe engaged between the support and the beater of each set. The shoe is advanced rearwardly between the two sets of pressing devices which move relatively away from and toward each other during the rearward movement of the shoe so as to follow the contour of the shoe at all times. To enable the sets of pressing devices to move relatively so as to follow the contour of the shoe, each of the carriers 10 is provided at its rear end with spaced arms embracing a supporting block 24 and is pivoted upon bearing pins 22 passing through the arms of the carrier and

threaded into the supporting block. Each supporting block is carried by guide blocks 25 mounted on a shaft 26 to turn about said shaft. The shaft 26 is journaled in bearings 27 carried by suitable arms on the frame of the machine and constitutes the main shaft of the machine from which the moving parts are actuated. This manner of mounting the carriers enables the sets of pressing devices to swing toward and from each other in planes containing the axis of the main shaft 26. The carriers also can swing about the shaft 26 to enable the sets of pressing devices to move vertically to conform independently to the transverse curvature of the shoe bottom. In order to support the carriers vertically the frame is formed with supporting arms 28 arranged to engage abutment faces formed on the carriers.

The carriers are connected by a coiled spring 30 which constantly tends to swing the carriers toward each other. During the movement of the shoe between the supports 2 the spring 30 through its action on the carriers maintains these supports constantly in engagement with the upper of the shoe. These supports thus act as guides and through the coöperative action of the supports and the spring 30, the pressing devices are caused to follow the outline of the shoe. The swinging movements of the carriers toward each other under the action of the spring 30 is limited by the engagement of a stop projection 32 formed on each carrier with the side of the corresponding arm 28.

With the two sets of pressing devices arranged in the manner above described, the shoe may be fed rearwardly between the same by the operator to cause said devices to act progressively on the parts of the shoe from the toe toward the heel thereof. In the present construction, however, the pressing devices are actuated to feed the shoe. When the beater 4 of one set of pressing devices is engaged with the outsole, the marginal portion of the outsole and the projecting sole portion of the shoe are securely gripped between the corresponding support 2 and the beater, and when the beater is disengaged from the outsole the shoe is free to be moved rearwardly relatively to the set of pressing devices. Each set of pressing devices is reciprocated forwardly and rearwardly in timed relation to the movements of the corresponding beater to feed the shoe, the rearward movement of each set occurring while the parts of the shoe are gripped between the beater and the support 2, and the forward movement thereof when the beater is disengaged from the outsole. The feeding movements of the two sets of pressing devices occur alternately, one set being moved rearwardly to feed the shoe while the other set is moved forwardly, so that a substantially constant rearward feeding

movement is imparted to the shoe and that the feeding movement of the shoe is positively controlled at all times by the pressing devices. The forward and rearward movements are imparted to the two sets of pressing devices by mechanism acting to reciprocate the carriers 10 longitudinally.

The mechanism for oscillating the beater supporting arms 15 and the mechanism for reciprocating the carriers 10 will now be described. Each of the arms 15 is secured to the forward end of a rock shaft 36 mounted in a bearing in the carrier 10. To the rear end of the shaft 36 is secured an arm 38 carrying at its outer end a pivoted block 40 engaging in a slot 42 in an eccentric block 44 surrounding an eccentric 46 secured to the main shaft 26. Each eccentric block 44 is formed with guide arms 48 engaging in guides in the corresponding block 24. The eccentric block is thus held from turning movement relatively to the block 24 and to the carrier 10. To enable forward and rearward reciprocating movements to be imparted to each of the carriers 10, each of the supporting blocks 24 is mounted to slide on the corresponding guide blocks 25, and to this end each supporting block is formed with parallel guide-ways in which the respective guide blocks therefor engage. The vertical movements imparted to the eccentric blocks 44 by the eccentrics 46 through the connections described will impart oscillating movements to the beater supporting arms 15. The forward and rearward movements of the eccentric blocks through the engagement of the guide arms 48 with the blocks 24 will impart forward and rearward movements to said blocks and to the carriers 10. The two eccentrics 46 are mounted on the shaft so that the carriers 10 will be alternately moved forwardly and rearwardly, these movements of the carriers occurring in timed relation to the movements of the respective arms 15 so that the pressing devices will act alternately to grip and feed the shoe rearwardly.

The driving mechanism for the main shaft 26 comprises a driving clutch member 52 mounted to turn loosely on the shaft and to receive a suitable driving belt, and a driven clutch member 54 secured to the outer end of the shaft. The driving clutch member 52 is also movable longitudinally of the shaft 26 to carry the same into and out of engagement with the driven clutch member 54, and is normally held out of engagement with the latter clutch member by a coiled spring 56. The driving clutch member 52 is adapted to be moved longitudinally of the shaft 26 into engagement with the driven clutch member 54 by means of a vertically movable clutch operating wedge 56 interposed between the right hand bearing 27 and a thrust block 57 arranged to act on the clutch mem-

ber 52 through a ball thrust bearing 58. A rod 59 is secured to and preferably formed integral with the lower end of the wedge 56 and is arranged to slide vertically in a guide-way in the outer end of an arm 60 formed on the frame of the machine. The wedge 56 is normally maintained in its upper position, allowing the members of the clutch to be held out of engagement by means of a coiled spring 61 surrounding the rod 59 and interposed between a collar 62 secured on the rod and the arm 60. The upward movement of the wedge 56 under the influence of the coiled spring 61 is limited by the engagement of a collar 63 secured to the lower end of the rod 59 with the arm 60. The wedge 56 is arranged to be actuated from a treadle to engage the members of the clutch, and to this end the wedge carries a pin 64 arranged to be engaged by the outer end of an arm 65 secured to a rock shaft 66. To the rock shaft 66 is clamped a second arm 67 having an opening in its outer end through which passes loosely a treadle rod 68 engaging in a guide in a projection 70 on the frame. The treadle rod 68 is arranged to be elevated by the actuation of the treadle to start the machine, and as the treadle rod 68 is elevated the arm 67 is swung upwardly by the engagement of a collar 72 mounted on the treadle rod with the lower side of the arm 67. By this movement of the arm 67 the arm 65 is swung downwardly and the wedge 56 is depressed to carry the driving clutch member 52 into engagement with the driven clutch member 54. The treadle rod is normally held in depressed position with the collar 72 in engagement with the projection 70 on the frame by means of a coiled spring 74.

To enable the machine to be run continuously when desired, a locking lever 76 is pivoted at 78 on an arm on the right hand bearing 27 and is arranged to engage the upper end of the wedge 56. When it is desired that the engagement and disengagement of the members of the driving clutch shall be controlled from the treadle, the locking lever 76 is swung into the position shown in full lines in Fig. 2. With the locking lever in this position the members of the clutch are disengaged upon each release of the treadle. When it is desired that the machine shall be driven continuously the locking lever 76 is swung into the position shown in dotted lines in Fig. 2. When located in the latter position the locking lever will lock the wedge 56 in its lowermost position, thereby holding the members of the driving clutch in engagement.

In the illustrated construction the stop projections 32 on the carriers are arranged to stop the relative swing movement of the carriers toward each other with the sets of pressing devices substantially in the relative

positions shown in Fig. 1. With the parts in the relative positions shown in this figure, the supports 2 are separated far enough to enable the toe of a pointed toed shoe to be inserted between the same, with the projecting margin of the sole engaged between the supports and the beaters in position to start the operation, and the pressing devices will be separated readily by the rearward movement of the shoe. To enable a round or blunt toed shoe to be inserted between the supports 2 in position to start the operation, mechanism arranged to be actuated from the treadle is provided for moving the carriers 10 relatively away from each other to separate the supports 2. In the illustrated construction this mechanism is arranged to be actuated to separate the supports 2 by the movement of the treadle before the clutch 20 is engaged to start the machine. This mechanism comprises a wedge 80 adjustably mounted on the upper end of the rod 68 and arranged to engage anti-friction rolls 82 mounted on arms 84 formed on the carriers 25 10. In order to guide the wedge 80, the wedge is formed on its rear side with a rib which engages between guide flanges projecting from an arm 85 on the frame and the wedge is provided with a slot 86 in which 30 engages a shouldered screw 88 threaded into the arm 84. As illustrated in the drawings, the upper end of the rod 68 is threaded into the wedge 80 so that the wedge may be adjusted longitudinally of the rod. The clamp 35 connection between the arm 67 and the rock shaft 66 enables the arms 65 and 67 to be relatively adjusted angularly. When narrow or pointed toed shoes are to be operated upon the wedge 80 is adjusted on the treadle rod 40 68 and the arms 65 and 67 are relatively adjusted so that the wedge 56 is actuated by the engagement of the arm 65 with the pin 64 to engage the clutch and the upward movement of the wedge 80 is thereby limited 45 before the latter wedge is engaged with the rolls 82. When round toed shoes are to be operated upon the wedge 80 is adjusted on the rod 68 and the arms 65 and 67 are relatively readjusted so that the wedge 80 will 50 engage the rolls 82 and swing the carriers 10 outwardly to separate the supports 2 before the wedge 56 is actuated by the engagement of the arm 65 with the pin 64 to engage the clutch. The separation of the supports 2 55 enables the shoe to be inserted between the same in position to start the operation before the machine is started.

The above described machine is adapted for use in the application of soles to shoe bottoms in the manufacture of shoes of various other classes than those of the Good-year welted shoe type as, for example, in the manufacture of McKay shoes in which the sole portion of the shoe secured to and 60 projecting beyond the upper is formed by

a welt or by the projecting margin of an intermediate sole, and in the manufacture of so called stitched down shoes in which this projecting sole portion of the shoe is formed by a flange on the upper. 70

Certain features of the invention also are not limited to machines for securing a sole to a shoe bottom but may be embodied in machines for performing various other operations upon the sole or bottom portions 75 of shoes after the uppers and soles are assembled. Certain features of the invention also may be employed in machines for operating on soles before they are applied to shoe bottoms. 80

Having explained the nature and object of the invention, and having specifically described the machine embodying the various features in the preferred form, what is claimed is:

1. A machine for operating on the marginal portions of shoe soles having, in combination, two sets of pressing devices for engaging and pressing together the marginal portion of an outsole and a sole portion of a shoe attached to and projecting beyond the upper arranged to act simultaneously and progressively on opposite sides of the shoe as the shoe is fed past said devices. 90

2. A machine for operating on the marginal portions of shoe soles having, in combination, two sets of pressing devices for engaging and pressing together the marginal portion of an outsole and a sole portion of a shoe attached to and projecting beyond the upper arranged to act simultaneously and progressively on opposite sides of the shoe as the shoe is fed past said devices, and means for supporting and controlling said sets of devices so that they will follow the contour of the shoe bottom. 100

3. A machine for operating on the marginal portions of shoe soles having, in combination, two sets of pressing devices for engaging and pressing together the marginal portion of an outsole and a sole portion of a shoe attached to and projecting beyond the upper arranged to act simultaneously and progressively on opposite sides of the shoe as the shoe is fed past the same, and means for actuating said devices to feed the shoe. 110

4. A machine for operating on the marginal portions of shoe soles having, in combination, two sets of pressing devices for engaging and pressing together the marginal portion of an outsole and a sole portion of a shoe attached to and projecting beyond the upper arranged to act simultaneously and progressively on opposite sides of the shoe and to support the shoe as the shoe is fed past the same, and mechanism for feeding the shoe. 120

5. A machine for operating on the mar- 130

ginal portions of shoe soles having in combination, two carriers pivoted to swing in substantially the same plane, two sets of pressing devices for engaging and pressing together the marginal portion of an outsole and a sole portion of a shoe attached to and projecting beyond the upper, respectively mounted on said carriers and arranged to act simultaneously and progressively on opposite sides of a shoe, guiding means mounted on the carriers and arranged to engage the shoe, and means acting yieldingly on the carriers and tending to swing the same toward each other to maintain the guiding means in contact with the shoe so that the pressing devices will follow the contour of the shoe.

6. A machine for operating on the marginal portions of shoe soles having, in combination, two sets of pressing devices for engaging and pressing together the marginal portion of an outsole and a sole portion of a shoe attached to and projecting beyond the upper, arranged to act simultaneously and progressively on opposite sides of the shoe, and means for movably supporting said sets of devices arranged to permit the same to move independently in directions transverse to the plane of the shoe bottom.

7. A machine for operating on the marginal portions of shoe soles having, in combination, two sets of pressing devices for engaging and pressing together the marginal portion of an outsole and a sole portion of a shoe attached to and projecting beyond the upper arranged to act simultaneously and progressively on opposite sides of the shoe, and two carriers respectively supporting said sets of pressing devices pivoted to swing independently about a common axis in planes transverse to the plane of the shoe bottom.

8. A machine for operating on the marginal portions of shoe soles having, in combination, two carriers pivoted to swing substantially in the same plane, two sets of devices for engaging and gripping intermittently the marginal portion of an outsole and the sole portion of a shoe secured to and projecting beyond the upper to press the same together, respectively mounted on said carriers and arranged to act simultaneously and progressively on opposite sides of the shoe, means for yieldingly swinging the carriers toward each other, guiding means mounted on the carriers and co-operating with said first means to cause the gripping devices to follow the contour of the shoe, and means for reciprocating the carriers in timed relation to the action of the gripping devices to feed the shoe.

9. A machine for operating on the marginal portions of shoe soles having, in combination, two sets of devices arranged to act

simultaneously and progressively on opposite sides of a shoe and each comprising a support arranged to act on one side of the projecting sole portion of the shoe, and a beater arranged to act on the opposite side of the projecting sole portion of the shoe, and means for actuating the beaters.

10. A machine for operating on the marginal portions of shoe soles having, in combination, two sets of devices arranged to act simultaneously and progressively on opposite sides of a shoe, and each comprising a support arranged to act on one side of the projecting sole portion of the shoe, a beater arranged to act on the opposite side of the projecting sole portion of the shoe, means for actuating the beaters, and means for actuating said sets of devices to feed the shoe.

11. A machine for operating on the marginal portions of shoe soles having, in combination, two sets of devices arranged to act simultaneously and progressively on opposite sides of a shoe, and each comprising a support arranged to act on one side of the projecting sole portion of the shoe, and a beater arranged to act on the opposite side of the projecting sole portion of the shoe, means for actuating the beaters, and means for supporting and controlling said sets of devices so that they will follow the contour of the shoe as the shoe is fed past the same.

12. A machine for operating on the marginal portions of shoe soles having, in combination, two sets of pressing devices arranged to act simultaneously and progressively on opposite sides of a shoe sole, and each comprising members arranged to receive the marginal portion of the shoe sole between them and operating to press the layers thereof together as the sole is fed past the same, and means for supporting and controlling said devices so that they will follow the contour of the sole.

13. A machine for operating on the marginal portions of shoe soles having, in combination, two sets of pressing devices arranged to act simultaneously and progressively on opposite sides of a shoe sole, and each comprising members arranged to receive the marginal portion of the shoe sole between them and operating to press the layers thereof together as the sole is fed past the same, means for supporting and controlling said devices so that they will follow the contour of the sole, and means for actuating said sets of devices to feed the sole.

14. A machine for operating on the marginal portions of shoe soles having, in combination, two sets of devices for gripping the projecting sole portion of a shoe, arranged to act simultaneously and progressively on opposite sides of a shoe, and means for actuating said devices to feed the shoe.

15. A machine for operating on the marginal portions of shoe soles having, in com-

bination, a support arranged to act progressively on one side of the projecting sole portion of a shoe, movably mounted so as to conform to the transverse curvature of said sole portion as the shoe is fed past the same, a beater arranged to act on the opposite side of the projecting sole portion of the shoe, and means for actuating the beater.

16. A machine for operating on the marginal portions of shoe soles having, in combination, two sets of pressing devices arranged to act simultaneously and progressively on opposite sides of a shoe, and each comprising members arranged to receive the projecting sole portion of the shoe between them.

17. A machine for operating on the marginal portions of shoe soles having, in combination, two sets of pressing devices for engaging and pressing together the marginal portion of an outsole and a sole portion of a shoe attached to and projecting beyond the upper arranged to act simultaneously and progressively on opposite sides of the shoe, and means for feeding the shoe past said devices constructed and arranged to control positively at all times the feeding movements of the shoe.

18. A machine for operating on the marginal portions of shoe bottoms, having, in combination, two sets of devices arranged to engage simultaneously a shoe at opposite

sides of the shoe bottom and means for actuating said devices to feed the shoe.

19. A machine for operating on the marginal portions of shoe bottoms, having, in combination, two sets of devices arranged to engage simultaneously a shoe at opposite sides of the shoe bottom and means for actuating said devices to produce and at all times to control the feeding movements of the shoe.

20. A machine for operating on the marginal portions of shoe bottoms, having, in combination, two sets of devices for gripping the projecting sole portion of a shoe arranged to act simultaneously on opposite sides of a shoe, means for actuating said devices to grip and release the sole and means for reciprocating said sets of devices in timed relation to each other to feed the shoe.

21. A machine for operating on the marginal portions of shoe bottoms having, in combination, two sets of devices arranged to act simultaneously and progressively on a shoe at opposite sides of the shoe bottom and two carriers for supporting respectively said sets of devices pivoted to swing in the plane of the shoe bottom toward and from each other and also pivoted to swing independently of each other in planes transverse to the plane of the shoe bottoms.

FREDERICK M. FURBER.
